THYRITE PROTECTIVE DEVICE

George Lindley Usselman, Port Jefferson, N. Y.,
assignor to Radio Corporation of America, a
corporation of Delaware

Application October 2, 1936, Serial No. 103,643

2 Claims. (Cl. 201—76)

This invention relates to an improved protective device and more particularly to a circuit protective device for the protection of apparatus subjected to high voltage surges, such as 5 filament bypass condensers and filament transformers generally employed in a transmitting circuit.

Filament bypass condensers and transformers have heretofore been manufactured with a sufficiently high safety factor above its normal working voltage so that it was not generally necessary to employ any protective device to protect the condensers and transformers against occasional increased voltages. However, with the 15 advent of mercury vapor tube rectifiers now employed in the higher powered transmitters, trouble with condenser and transformer failure has greatly increased due to higher voltage surges. Several attempts have been made to 20 protect the condensers and transformers, such as to shunt spark gaps in rare gas across the condensers for protection, but this method has not proven to be reliable.

In the present invention, the filament bypass 25 condensers and filament transformers are protected by novel circuits employing a particular form of material, sold under the name "Thyrite," which is described more fully in United States Pat. #1,822,742, to McEachron, of September 3, 1931, and the "General Electric Review" for February, 1930, pages 92 to 100 (vol. 33, No. 2).

The use of this "Thyrite" protective device permits the use of lower voltage bypass condensers, and consequently larger capacity can 35 be obtained in the same size condenser case.

The present invention will best be understood by referring to the accompanying drawings, in which:

Fig. 1 is a wiring diagram of a transmitter 40 circuit wherein the bypass condensers are protected by "Thyrite" discs;

Fig. 2 is an elevation partly in section of the "Thyrite" protective device;

Fig. 3 is an end view of Fig. 2;

Fig. 4 is another embodiment of a "Thyrite" 45 protective device; while

Fig. 5 is an end view of Fig. 4.

Referring now in detail to Fig. 1 of the drawings, an abbreviated transmitting circuit is 50 shown which employs a protective device 1, which is made up of alternate plates or discs 2 of "Thyrite" and metallic electrodes 3, 4 and 5, the electrodes 3 and 4 each being attached to a terminal of filament bypass condensers 6 and 7 55 which are to be protected. The other electrodes

5 and 5' are connected to ground. From the circuit, it will be noted that the "Thyrite" is in parallel with the apparatus to be protected. In this case, the center points of the condensers 6 and 7 are connected to ground. The two outside terminals of the condensers are connected to the filament leads of the tube 8. The purpose of the bypass condensers 6 and 7 is to act as a radio frequency bypass to prevent the radio frequency from entering and damaging the filament 10 transformer 9. It is also necessary that the filament leads be grounded for radio frequency currents for the proper operation of a transmitter.

During the operation of high powered transmitters employing mercury vapor tubes there frequently occurs an arc-over, due to various causes, 15 across the neutralizing condenser 10 or in the tube 8, itself. In either case, the result is an instantaneous discharge of the smoothing condenser 11 in a high voltage rectifier 12. This 20 discharge enters the filament of tube 8 and when protective devices are not used the current of the discharge must flow through the secondary winding of the filament transformer 9, through the impedance 13 to ground. The impedance 13 25 may be such apparatus as overload relays, meters, resistors, etc.

In any case, the impedance 13 is usually high enough to cause abnormal voltages to occur from the terminals of condensers 6 and 7 to ground. 30 It is not practical for certain reasons, such as space requirement and high manufacturing cost, to make the voltage rating of the condensers high enough to withstand more than about one-tenth of the full rectifier voltage. However, in 35 practical operation, condensers 6 and 7 are subject to several times their voltage rating when an arc-over, as mentioned above, occurs. This results in frequent condenser and filament transformer failures which continue to occur unless proper means of protection is used. A modulated 40 source of high frequency oscillations 14 is connected to the grid coupling condenser 15 and ground 16.

"Thyrite" has the property of decreasing in 4 resistance with an increase of current through it, which follows the law given more fully in the February, 1930, issue of "General Electric Review," and the McEachron Pat. #1,822,742, of current = $KV^{3.57}$, where V is the voltage across 50 the "Thyrite" material, and K is some constant depending upon the size and type of the "Thyrite" plate. When the voltage is doubled, the current through the "Thyrite" plate increases about twelve times so that it will be seen that 55

this material is ideal for a condenser protective device, and with proper mounting will protect the bypass condensers and filament transformers from dangerous voltages which might cause insulation failures of the transmitter, and as a consequence interruption of service.

Referring now to Figs. 2 and 3 of the drawings, a simple circuit protective device is shown which employs four "Thyrite" discs 21 which are assembled on an insulating rod 30 and clamped between two insulating end plates 22 of suitable insulating material. Two springs 23 are arranged each side of the discs 22 to press the "Thyrite" discs and electrodes together. The electrodes 24, 25, 26, 27 and 28 are sandwiched in between the "Thyrite" discs 21 and in case of electrodes 27 and 28 between discs 21 and end plates 22. It is, of course, to be understood that the number of "Thyrite" discs may be increased in even number up to twelve, or even more discs, to increase the current rating of the protective device.

The discs 21 and insulating members 22 and the electrodes or terminals 23 to 28 inclusive are all provided with a central aperture through which passes the insulating rod 30. At each end of insulating rod 30 there is provided mounting brackets 31 and 32, rod 30 being secured to the mounting brackets by suitable screws 33 and 34. To electrically connect the protective device to the condenser, there are provided mounting brackets 31 and 32 which are then secured to members 35 and 36. The outside members 25 and 26 and center terminal 24 are joined together by means of a clamping strip 24' which is electrically connected by means of flexible lead 39 to a ground terminal 39' on the frame of the transmitter. The electrode members 27 and 28 are connected to terminal members 36 and 35 by means of nuts on the two screws 32 and 31, respectively. The terminal members 36 and 35 are connected to the terminals of the condensers 6 and 7, as shown in Fig. 1. The midpoint of the condensers is connected to the condenser case and thence to ground.

The protective device shown in Figs. 4 and 5 is particularly adapted to transmitting circuits wherein a larger current carrying device is desired. The general arrangement is similar to that shown in Figs. 1 to 3 inclusive, except that the overall dimensions of the "Thyrite" discs and their number employed are increased. The "Thyrite" discs 40 are interposed between a pair of copper cooling fins 41 and are spaced apart

from the adjacent group by a pair of spacing discs 42, preferably of aluminum. Members 40 to 42 inclusive are provided with a suitable aperture or hole through which an insulated rod or sleeve 43 passes. At each end of the protective unit there is located a cup-shaped disc-like spring element 44. A rod 45 which is threaded at each end passes through sleeve 43 and the entire unit is tightly clamped together by means of nuts 46, and a pair of end mounting members 47 is located at the end of nuts 46 and is securely fastened to the protective device by means of nuts 48. Holes 49 and 50 are provided in plates 41, as shown in Fig. 5, for electrical connection to the "Thyrite" protective device. With this arrangement, most any desired connection, such as series or parallel, may be obtained.

What is claimed is:

1. An electrical protective device comprising an alternate assembly of annular "Thyrite" discs 20 and annular metallic electrodes, each electrode having a projecting lug, an insulating washer at each end of said assembly, an insulating rod 25 passing through said assembly, binding means for maintaining said assembly in intimate contact including an L shaped metallic support at each end of said rod, and a spring member between each of said supports and said insulating washers, terminal lug extensions on each of said L shaped members and an insulating supporting strip between said members, the central and end electrodes of said assembly being connected together and connected to ground, connections from each of the intermediate electrodes to a corresponding one of said terminal lug extensions, said lug extensions being adapted to be connected to an 30 electrical circuit to be protected.

2. An electrical protective device comprising an assembly of annular "Thyrite" discs and annular metallic electrodes, each electrode having a projecting lug, an insulating washer at each end of 40 said assembly, an insulating rod passing through said assembly, binding means for maintaining said assembly in intimate contact including an L shaped metallic support at each end of said rod and a spring member between each of said supports and said insulating washers, terminal lug extensions on each of said L shaped members and an insulating supporting strip between said members, the central and end electrodes of said assembly being connected together and connections 50 from each of the intermediate electrodes to a corresponding one of said terminal lug extensions.

GEORGE LINDLEY USSELMAN.
